CLAIM

The ornamental design for an engine air intake vortex plate, as shown and described.

DESCRIPTION

FIG. 1 is a top perspective view of an engine air intake vortex plate, showing my new design;
FIG. 2 is a bottom perspective view thereof;
FIG. 3 is a side elevational view, the opposite side being a mirror image thereof;
FIG. 4 is a top plan view thereof; and,
FIG. 5 is a bottom plan view thereof.
